FOLDING CART

Jerome M. St. Paul, Scarsdale, N. Y.

Application October 24, 1947, Serial No. 781,876

3 Claims. (Cl. 280—42)

1

This invention relates to a folding cart. The device disclosed herein is adapted for example to transport food and the like and when not in use may be collapsed into a minimum of space.

An object of the invention is to provide a simple and practical device of the above described kind.

Another object of the invention is to provide means for transporting food and the like while protecting it from flies and other insects.

Another object of the invention is to provide a folding cart adapted in use to comprise a container for transporting food, glasses or other objects, which may be collapsed to occupy a minimum of space when not in use.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which:

Figure 1 is a front elevation;

Figure 2 is an end elevation;

Figure 3 is a top plan view;

Figure 4 is an end plan view of the structure when folded;

Figure 5 is a fragmentary end view showing hinge mounting means for a tray or cover member by which the member may be swung through 270°; and

Figure 6 is a detail plan view showing the handle mounting means.

In the embodiment of the invention shown herein the structure comprises non-collapsible sides, collapsible ends, a bottom and, if desired, one or more shelves which are adapted to fold into planes parallel with the side walls, and a top member adapted to serve as a tray or the like and movable from a horizontal operative position at the top of the structure into a vertical plane substantially parallel with the sides of the structure.

As illustrated the frame of the device comprises the upright frame members 10 and 12 which are similar except that the posts 12 defining one end of the structure are longer than the posts 10 defining the other end of the structure and are adapted to rest directly on the ground or other supporting surface whereas members 10 are supported at the lower end by wheels 14 mounted on axles 16 the rear ends of which are received in an enlarged portion 18 provided at the lower end of members 10 respectively.

2

Between corresponding pairs of members 10 and 12 are the upper and lower side frame members 20 and 22 respectively and these are interconnected intermediate their ends by vertically extending cross bar 24, which together with said members 10 and 12 and 20 and 22 define spaces in which the doors 26 and 28 are pivotally mounted as by means of hinges 30.

Between the sides of the structure two part folding end members are provided comprising the portions 32 and 34, joined together along a vertical median line 36 by hinges 38. The members 32 and 34 forming the closure for the end of the structure supported on the wheels 14 are supported along their marginal edges from the frame members 10^a (similar to members 12^a), which extend laterally from the members 10, by hinges 40, and the similar members 32 and 34 closing the other end of the structure are similarly supported from upright frame members 12^a similar to members 10^a. Members 10^a and 12^a are of less thickness than members 10 and 12 leaving room on members 10 and 12 for the attachment of hinges 46 and 54 as will be explained. The end members may thus be collapsed inwardly into the position shown in Figure 4 when the cart is not in use.

The bottom of the cart comprises the two portions 42 and 44 hinged along their outer margins by hinges 46 to the vertical frame members 10 and 12 respectively so that they may be moved from a substantially horizontal operative position to a substantially vertical position, as indicated by the dotted lines in Figure 2, when it is desired to collapse the cart. Stops 48 are provided on the inner surface of said end members 32 and 34 respectively, at a height to position and support said members 42 and 44 with their inner margins in abutting relationship in a substantially horizontal plane. If desired one or more shelves may be provided similar in construction to the bottom. One such shelf is illustrated in Figure 2 comprising the two halves 50 and 52 hinged to members 10 and 12 respectively by hinge members 54, and positioned and supported in its unfolded operative position by stop means 56 secured on the inner surface of said end members 32 and 34 respectively.

Positioned on top of the structure provided is 50 a tray-like member 58 forming a cover for the structure defined by the side and end walls and the bottom and cooperating with said side and end walls and said bottom to form a closure adapted to receive food for example and protect it from flies and other insects, and from wind and rain etc. while it is being transported. This member may be provided with receptacles 60 to receive glasses as indicated in Figure 3.

Member 58 is secured to the vertical frame members 10 and 12, on one side of the structure,

by hinges 62 comprising four leaves, pivotally joined together whereby the tray may be swung outwardly from its operative horizontal position through 270° to a vertical position in a plane parallel with the planes of the sides of the structure, which is its position when the cart is collapsed.

A handle 64 is provided which extends between the vertical posts 12 when the structure is in operative position, but which may be detached from one of said posts and moved into a vertical plane when it is desired to collapse the cart. One end of the handle is attached to one of the members 12^a by a universal joint, which, as shown in Figure 6, comprises a bracket or socket 66 projecting from one of said members 12^a and acting as a cage in which is seated the ball-like member 68 provided at one end of said handle 64. Bracket 66 is open at the front and the ball 68 is retained therein by the nut 69. The other end of said handle 64 is received in a semi-circular flange 70 projecting from the other upright 12^a and open at its under side to receive the other end of handle 64 which may be swung up into it on said universal joint provided at the opposite end of handle 64. Holes 64^a and 79^a are provided extending diametrically through the end of the handle remote from said universal joint, and through the socket 70 and positioned to be in register when handle 64 is in operative position whereby the free end of said handle may be secured to bracket 70 by inserting the pin 72 through the said holes provided in said bracket 70 and the free end of said arm 64. When it is desired to collapse the structure it is only necessary to withdraw pin 72 in order to release the arm 64 from bracket 70 after which arm 64 will swing down and occupy a position in the same plane with the upright frame post 12^a to which it is attached by said universal joint.

Thus the structure may be easily collapsed from the operative position shown in Figures 1, 2, and 3 to the collapsed position shown in Figure 4 with the cover or tray 58 and the handle 64 hanging down in vertical planes substantially parallel with one another and with the sides of the cart. It will be apparent that the collapsed cart may be stored away in only a fraction of the space required for the structure when in operative position and may be readily transported from one place to another.

It will thus be seen that there has been provided by this invention a structure in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. A folding carrier for food and the like comprising non-collapsible side walls, collapsible end walls hingedly connected at either lateral margin to said side walls, each of said end walls being divided along its vertical median line, and hinge means interconnecting the end portions thus defined, a divided bottom comprising two parts and hinge means interconnecting said parts

5 and said side walls respectively, and a handle pivotally mounted at one end on the end of one of said side walls, and a bracket mounted on the end of the other side wall and partly open to receive the end of the handle which is remote from said pivotal mounting, said bracket and said handle having holes therethrough adapted to be in alignment when said handle is operatively positioned transversely of said carrier, and pin means adapted to be inserted through said aligned holes to secure the said end of the handle in said bracket.

2. A folding carrier for food and the like comprising non-collapsible side walls, collapsible end walls hingedly connected at either lateral margin to said side walls, each of said end walls being divided along its vertical median line, and hinge means interconnecting the end portions thus defined, a divided bottom comprising two parts and hinge means interconnecting said parts and said side walls respectively, and a member adapted to extend over the closure formed by said side and end walls and said bottom when the structure is unfolded, and hinge means each comprising four pivotally related leaves interconnecting the said member and one of the said sides, the outside hinge leaves being connected to said member and to the said side of the carrier, and the two middle leaves of said hinge means being pivotally joined together and also pivotally joined respectively to said outside hinge leaves whereby said member may be rotated through 270° from a substantially horizontal position to a substantially vertical position.

3. A folding cart comprising side walls, end walls hinged to the side walls respectively, and each comprising two portions hinged together along a central vertical line whereby said ends may be folded so that the said portions thereof 40 occupy substantially parallel planes, and a divided bottom comprising two parts hinged respectively to said side walls and each movable from a position at right angles to the side wall from which it is hinged into a position in a plane 45 substantially parallel with the side wall, hinge means joining said bottom portions to said side walls respectively, stop means on the inside of the said end walls respectively adapted to position and support said bottom members when the 50 said cart is in unfolded position, a tray hingedly mounted on one of said side walls, and hinge means for supporting said tray on said side wall so that the tray is positioned within the perimeter described by the side and end walls when the 55 cart is in open, operative position, and may be swung into a plane substantially parallel with the side walls of said cart when said cart is collapsed.
